A. SPRUNG

ILLUMINATED TRAFFIC SIGNAL STANDARD

Filed July 25, 1925

Inventor

Abraham Sprung

By his Attorney

Charles L. Wright

UNITED STATES PATENT OFFICE.

ABRAHAM SPRUNG, OF NEW YORK, N. Y., ASSIGNEE TO MUNICIPAL STREET SIGN CO. INC., OF NEW YORK, N. Y., A CORPORATION OF NEW YORK.

DESIGN FOR ILLUMINATED TRAFFIC-SIGNAL STANDARD.

Application filed July 25, 1925. Serial No. 14,923. Term of patent 7 years.

To all whom it may concern:

Be it known that I, ABRAHAM SPRUNG, a citizen of the United States, residing in New York, in the county of New York and State of New York, have invented a new, original, and ornamental Design for Illuminated Traffic-Signal Standards, of which the following is a specification, reference being had

to the accompanying drawing, forming part thereof.

The figure is a front elevational view of the illuminated traffic signal standard.

I claim:

The ornamental design for illuminated traffic signal standard as shown.

ABRAHAM SPRUNG.
